UNITED STATES PATENT OFFICE.

JOHN B. HADAWAY, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SHOE-TREATING APPARATUS.

1,410,470.

Specification of Letters Patent. Patented Mar. 21, 1922.

Application filed April 12, 1919. Serial No. 289,570.

To all whom it may concern:

Be it known that I, JOHN B. HADAWAY, a citizen of the United States, residing at Swampscott, in the county of Essex and State of Massachusetts, have invented certain Improvements in Shoe-Treating Apparatus, of which the following description, in connection with the accompanying drawings, is a specification, like reference characters on the drawings indicating like parts in the several figures.

This invention relates to apparatus for treating shoes and more especially to the treatment by which portions of shoes are softened preparatory to lasting.

It has become very common, if not universal, practice to soften the toe-end of a shoe preparatory to lasting the shoe around the toe, in order to render the marginal portions of the shoe-upper and the toe-box sufficiently limp and pliable to enable these elements to be pulled over, crimped, lasted, and compacted readily upon the bottom of the insole without injuring the parts so worked. In accordance with this practice various forms of shoe-treating apparatus have been provided, and although some of them give satisfactory results within certain limits they are not entirely satisfactory for all kinds of work. For example, some kinds of upper-leather require a considerable quantity of moisture to render them soft and pliable, others respond to heat with a relatively small quantity of moisture, while materials such as those of which the so-called Beckwith box-toes are made become limp and pliable when heated without the addition of any moisture whatever. It is not, in any case, desirable to subject the work to any greater degree of moisture than that required to soften the parts that are to be pulled over and lasted, and consequently an apparatus that subjects the work to excessive moisture is open to the objection that some kinds of leather show stains and dry very slowly after being treated.

Considerable effort has been made to provide a shoe-treating apparatus capable of being regulated as to heat and moisture so that these factors can be altered instantly if necessary between the treatment of one shoe and the next, at the same time affording

a wide range of variation in the quantity of moisture and in the degree of heat administered to the work. This general object has not heretofore been obtained with a wholly satisfactory degree of success, one of the prominent difficulties being that the degree of temperature could not be maintained within bounds that safeguard the work from being burned. A serious disadvantage has been that an excessive quantity of steam or vapor has been discharged into the work-room, which is objectionable both for the reason that it renders the atmosphere of the work-room unhealthy and uncomfortable, and causes excessive rusting of the machinery therein. Moreover, a treating apparatus that depends for its supply of vapor or steam upon a remote source of supply necessitates piping that is objectionable in warm weather, that is wasteful, and that increases the cost of installing a treating apparatus.

One object of the present invention is to overcome formed difficulties and disadvantages, and to provide an apparatus adapted to treat various shoes by heat alone, by vapor, or by vapor and dry heat conjointly, at the same time affording all the degrees of regulation necessary to treat each shoe according to the mode of treatment best suited to the shoe.

An important feature of the invention consists in supplying vapor at atmospheric pressure to one part of the work, for example, the under side, and at the same time supplying dry heated air to that part of the work that does not require moisture, for example, that part of the toe portion that is visible when the shoe is finished.

Another important feature of the invention consists in utilizing one heating element to generate vapor for treating one part of the shoe and also for generating and heating a current of relatively dry air for treating another part of the shoe. In this connection a feature of the invention consists in means arranged to generate vapor and a current of heated air separately so that the vapor and heated air may be conducted respectively to those parts of the shoe that require different treatment.

According to the illustrated embodiment

of the invention the liquid to be vaporized is conducted from a barometric feeder to a heating element upon which the liquid is discharged at a rate within the capacity of 5 the heating element to convert it into vapor, so that a uniform head of liquid, and consequently a uniform rate of flow from the barometric feeder to the heating element, will be maintained notwithstanding descent 10 of the level of liquid in the container of the barometric feeder.

Other objects and features of the invention are disclosed by the following detailed description and claims in conjunction with 15 the accompanying drawings.

Referring to the drawings,—

Fig. 1 represents a perspective view of a treating device embodying the present invention in a form designed to treat one shoe 20 at a time, and

Fig. 2 represents a sectional view on a larger scale and in a vertical plane showing such apparatus equipped with a barometric feeder, a shoe being arranged in position 25 for treatment.

The treating device comprises a cast-iron casing 10 having a chamber 12 and a mouth 14 to receive a portion of a shoe for treatment. A structure 16 composed preferably 30 of heat-insulating material such as wood is attached by any suitable means to the front wall of the casing to determine the position of the shoe and to support the latter out of contact with the metal of which the casing 35 is made. This guard 16 is provided with a mouth 18 through which the toe end of a shoe may be inserted as shown by Fig. 1, the surface 20 of said guard serving as a support for the forepart of the shoe. The heel-part 40 of the shoe may be supported by any suitable means, such means, in the present instance including a bracket 22, a clamping bolt 24, and a washer 26. Portions of the bracket 22 are interposed between the guard 16 and 45 the washer 26 in such relation as to be clamped against the guard by the same pressure that clamps the guard against the casing. The guard is provided with a slot 28 that affords a range of vertical adjustment 50 relatively to the casing, and the bracket is likewise adjustable relatively to the casing and relatively to the guard. A holder 30 adjustably fitted to the bracket is formed and arranged to straddle the shoe so as to 55 keep the latter from being displaced laterally from the bracket.

An electric heating unit is indicated conventionally at 32. It is enclosed in a metallic shell 34, one end 36 of which extends 60 through a hole in a wall of the casing and fits closely in said hole. This end of the shell is open to permit the insertion and removal of the heating unit 34 while the shell and the casing remain in connected relation,

as shown. The electrical conductors for the 65 heating unit are indicated at 38, 40, the latter including a rheostat 42 having any desired number of points of regulation to afford variations in the heating effect of the unit.

The metallic shell 34 occupies the chamber 12 at a level below that of the work inserted through the mouth 14, and is arranged so that the inserted portion of the work will overhang it in order to utilize 70 heat and vapor most economically. The upper part of the shell 34 is provided with a trough 44 into which water may be fed drop by drop to be vaporized by the heating unit. When the shell is heated without having 80 a liquid fed to it, it heats the work by direct radiation without subjecting the work to any moisture, but when liquid is fed into the trough it is immediately vaporized and the vapor rises without pressure but merely 85 by levitation into direct contact with the work and without being deflected or otherwise guided. When this device is generating vapor it radiates dry heat at the same time, the dry heat rising and mingling with 90 the vapor. A screen 46 of fine mesh may be interposed between the vaporizer and the work but may be omitted if desired. This screen, as shown, is carried by an open frame 48 of sheet metal, the frame being detachable and of such proportions that it may be inserted through the mouth 14.

Fig. 2 includes means for feeding liquid drop by drop to the trough 44 without subjecting the shoe to the risk of being moistened by the liquid. The feeding means comprises a feed pipe 50 extending over and lengthwise of the trough 44 and having one or more small perforations in its under side to emit liquid drop by drop so that the drops 100 will enter the trough 44. The receiving end of this pipe is connected to a cup 52 of a barometric feeder supported externally of the casing 10. This cup, as shown, is fixed to the upper end of a post 54. The liquid 110 container 56, which is closed excepting at the bottom, is provided with a nozzle 58, and the latter is arranged in the cup 52 to be supported by ribs 60 formed in the cup. The nozzle contains a shut-off valve 62. The 115 lower end of the post 54 is provided with a screw-thread and with a nut 64 in the form of a hand wheel, such nut being arranged to be supported by a plate 66. The plate 66 is bolted to the upper end of a supporting 120 base or standard 68 which, for reasons about to be described, is preferably hollow.

The casing 10 is formed with a hollow stem 70 at its lower end, and said stem is arranged in telescopic relation to the hollow 125 standard 68. Although the lower portion of the standard is not shown, it will be open to the atmosphere so that a current of air

may flow upwardly through it and through the stem 70 so as to enter the casing 10. The casing is preferably provided with means forming a flue to guide the air separately 5 from the vapor.

According to the illustrated embodiment of the invention the flue-forming means comprises a tubular section 72 and a sheet metal section 74 forming a chamber 76. A portion 10 of the section 74 is shaped to conform to the heating shell 34 and is arranged in contact with the shell so as to absorb sufficient heat from the latter to induce an inflow of air through the stem 70. The air 15 thus drawn in is heated by contact with the sheet metal section 74 and rises by levitation to the upper part of the chamber 76 from which it is emitted through perforations 78. The upper part of section 74 is preferably 20 arranged to extend above and to overhang that portion of the shoe that is inserted through mouth 14. The perforations 78 may be located according to any preferred arrangement but in the form of apparatus 25 shown the greater number of perforations are above the portion of the work that is to be treated while a relatively small number of perforations are below the level of the work to emit heated air where it may mingle 30 with the vapor that is about to encounter the work. Those perforations that are above the work are so disposed as to emit the heated air downwardly at various angles of inclination so that a large number of small 35 jets of heated air will play upon the upper part of the work to prevent the upper part from being moistened appreciably by the vapor. In the event that the inserted toe portion of the shoe is provided with a toe- 40 box that is rendered soft and pliable by heat, for example, the so-called Beckwith toe-box, such toe-box will be softened throughout its entire area while only the depending marginal portion of the upper will be appreciably 45 moistened by any vapor that may rise from the trough 44.

The volume and temperature of air passing through the chamber 76 will depend to some extent upon whether the heating unit 50 is used at the same time for converting liquid into vapor, and to some extent upon the control afforded by the rheostat 42. It is obvious that when the heating unit is subjected to the cooling effect of cold water or other cold 55 liquid dropped upon it the proportion of heat absorbed by the air in chamber 76 will be less than when the air alone is absorbing the heat. This is as it should be because, when treating work that requires vapor, 60 there should not be too great a quantity of heated air nor too high temperature, since an excess of dry heat would neutralize the softening effect of the vapor. On the other hand, when the device is used to supply dry

heat without vapor the volume and temperature of the heated air are both greater. In every case, however, a relatively small quantity of liquid may be fed through pipe 50 to insure enough vapor to safeguard the work against being burned by excessively hot air. 65 The supply pipe 50 is provided with a regulating valve 80 for controlling the quantity of liquid supplied for vaporization.

The upper part of casing 10 is tapered toward the center and terminates in a cylindrical flue 82. This flue provides a convenient coupling for a pipe such as that indicated at 84 to conduct the waste vapor away from the device otherwise than by permitting it to escape into the workroom. The 75 coupling portion 82 is provided with an oscillatory valve 86 the stem of which has a head or knob 88 by which it may be turned to open and close the passageway.

Having thus described my invention, what 80 I claim as new and desire to secure by Letters Patent of the United States is:

1. A shoe-treating apparatus comprising means for supporting a shoe in position for treatment, a metallic element adjacent to the 90 treating locality, a conduit arranged to drip liquid upon the upper surface of said element, means for heating said element to vaporize the liquid so dripped upon it, and means for maintaining liquid at a constant 95 level in said conduit to maintain a constant rate of discharge of the liquid.

2. A shoe-treating apparatus comprising a treating device having a chamber, a metallic element arranged in said chamber, means 100 including a barometric feeder arranged outside said chamber for feeding liquid to a point from which it may gravitate to the upper surface of said element, and means for heating said element to vaporize the 105 liquid fed to the latter.

3. A shoe-treating apparatus comprising a treating device having a chamber and a mouth to receive an end of a shoe, a metallic element arranged in said chamber under the 110 position to be occupied by the work inserted into said mouth, liquid-feeding means including a conduit having an outlet arranged between said element and the level to be occupied by the work so that the discharged 115 liquid will drop upon said element, and means for heating said element to vaporize the liquid fed to the latter.

4. A shoe-treating apparatus comprising a treating device having a chamber, a metallic 120 shell having an external liquid-holding cavity in its upper side, said shell being arranged in said chamber, and an electric heating unit arranged in said shell.

5. A shoe-treating apparatus comprising 125 a treating device having a chamber, a metallic shell open at one end and arranged in said chamber, a wall of said chamber hav-

ing a hole and said open end of the shell being joined to said wall in registration with said hole, means for feeding liquid by gravity to the exterior surface of said shell, 5 and an electric heating unit arranged in said shell to vaporize the water fed to the latter, said unit being removable through said open end of the shell and through said hole while the shell and said wall are joined 10 as aforesaid.

6. A shoe-treating apparatus comprising a treating device having a chamber and a mouth to receive a portion of a shoe, means arranged to moisten a portion of the work 15 inserted in said mouth, and means arranged to discharge a current of air upon another portion of said work.

7. A shoe-treating apparatus comprising a treating device having a chamber and a 20 mouth to receive a portion of a shoe, means arranged to moisten a portion of the work inserted in said mouth, and means arranged to heat air and to discharge a current thereof upon another portion of the work.

25 8. A shoe-treating apparatus comprising a treating device having a chamber and a mouth to receive a portion of a shoe, vapor-generating means including a heating element arranged in said chamber, and means 30 including said heating element for supplying heated air separately from the vapor, the latter said means being arranged to discharge the heated air against the work inserted in said mouth.

35 9. A shoe-treating apparatus comprising a treating device having a chamber and a mouth to receive a portion of a shoe, means forming an air flue in said device, a heating element arranged in said chamber to 40 heat a portion of said flue-forming means, the flue being arranged to discharge the heated air against the work inserted in said mouth, and liquid-feeding means arranged to discharge liquid upon said heated element to supply vapor to the work.

45 10. A shoe-treating apparatus comprising a treating device having a chamber and a mouth for the reception of a portion of a shoe, means in said chamber for generating vapor and a current of hot air separately, and means for supplying a liquid to the first 50 said means to be vaporized thereby.

11. A shoe-treating apparatus comprising a treating device having a chamber and a 55 mouth to receive a portion of a shoe, means arranged to supply vapor to the under side of the work inserted in said mouth, and means arranged to emit air downwardly against the upper side of the work.

60 12. A shoe-treating apparatus comprising a treating device having a chamber and a mouth to receive a portion of a shoe, means arranged to supply vapor to the under side of the work inserted in said mouth, said 65 means including a heating element located

in said chamber, and means for supplying a current of air to the work, said air-supplying means being arranged to be heated by said heating element to heat the air supplied to the work.

70 13. A shoe-treating apparatus comprising a treating device having a chamber and a mouth to receive a portion of a shoe, means in said chamber for generating vapor and a current of hot air separately, and means for keeping the vapor and the hot air separate as they flow from the generating means to the work inserted in said mouth.

75 14. A shoe-treating apparatus comprising a treating device having a chamber and a mouth to receive a portion of a shoe, said device having a hole to admit air below the level of the work, means in said chamber forming a flue to conduct air from said hole to the work, vapor-generating means including a heating element in said chamber, said element being arranged to heat a portion of said flue-forming means so as to induce a current of air therein by levitation.

80 15. A shoe-treating apparatus comprising a casing forming a treating chamber and having an inlet opening to receive air, means in said chamber for supplying hot vapor to treat one portion of the work, means forming a flue to conduct the air from said inlet opening to another part of the work constructed and arranged to prevent the vapor from moistening said other part, and means for causing air to flow through said flue toward the work.

85 16. A shoe-treating apparatus comprising a treating device having a chamber, a base for supporting said device, said base and said device having co-operative telescopic portions for coupling them and for forming a 90 conduit to conduct air from the atmosphere into said chamber, and heating means in said chamber to generate an inflow of air through said telescopic portions and to heat the air for treating the work.

95 17. A vapor-treating apparatus comprising a metallic heating element, means arranged to drop liquid upon said heating element, said means including a barometric feeder arranged to control the supply of 105 liquid, and means arranged to support an article of work where it will undergo treatment by the vapor generated by said heating element.

10. A vaporizing apparatus comprising a hollow metallic element having an external trough for liquid to be vaporized, an electrical heating unit arranged in said metallic element to vaporize the liquid in said trough, and means, including a barometric feeder, 120 arranged to supply liquid by the force of gravity and to discharge the liquid above the level of said trough so as to drop the discharged liquid into said trough.

125 19. A vaporizing apparatus comprising a 130

heat-radiating element having an external trough arranged to hold liquid to be vaporized, heating means embedded in said element under said trough, and means arranged to supply liquid to said trough at a constant rate.

20. A treating apparatus comprising a casing having a treating chamber, a metallic heat-radiating element in said chamber, and 10 means including a barometric feeder ar-

ranged to drop liquid on the exterior of said element at a constant rate to be vaporized.

21. A vaporizing apparatus comprising an internally heated element, and liquid feeding means arranged to supply liquid to the exterior of said element at a constant rate to be vaporized. 15

In testimony whereof I have signed my name to this specification.

JOHN B. HADAWAY.
